HENRY W. WACHTELHAUSEN, OF MERIDEN, CONNECTICUT, ASSIGNOR TO THE PARKER CLOCK COMPANY, OF MERIDEN, CONNECTICUT, A CORPORATION OF CONNECTICUT.

SPRING-MOTOR.

1,159,437.

Specification of Letters Patent.

Patented Nov. 9, 1915.

Application filed May 14, 1915. Serial No. 27,988.

To all whom it may concern:

Be it known that I, HENRY W. WACHTELHAUSEN, a citizen of the United States, residing at Meriden, in the county of New Haven and State of Connecticut, have invented certain new and useful Improvements in Spring-Motors, of which the following is a specification.

This invention relates to spring motors. 10 It is conceivable that some or all of the features of the invention can be embodied with equal advantage in other devices.

The invention has as one of its objects the provision of means by which a motion transferring member can be operated in one direction to tension the spring of the motor but which can be freely operated in the other direction without affecting said spring, so that when the motor constitutes a part of a 15 20 wheeled toy, the spring of the motor can be wound to drive the toy whereas the toy can be pulled along without having any effect upon the spring which is a feature of importance as thereby there is no strain upon 25 the spring or any tendency to displace it when the toy is being pulled by a child instead of being operated by the motor.

Another feature of the invention resides in an inexpensive and simple frame which 30 incloses the motor and certain of the other parts, while still another point is in a very convenient way of connecting one end of the spring with the frame.

The invention possesses other features of 35 novelty and usefulness, which with the foregoing will be stated at length in the following description, wherein I will set forth in detail that one of the several convenient forms of embodiment of the invention which 40 I have selected for illustration in the drawings accompanying and forming part of the present specification. I do not restrict myself to this disclosure; I may depart therefrom in several respects within the scope of 45 the invention defined by the claims following said description.

Referring to said drawings: Figure 1 is a top plan view partly in section of a spring motor involving my invention. Fig. 2 is a side elevation with the face plate of the frame removed. Fig. 3 is a vertical section on the line 3—3 of Fig. 2 looking in the direction of the arrow.

Like characters refer to like parts throughout the several views.

The framing shown for carrying the different parts comprises a back plate 2 and a face plate 3, said back plate being illustrated as having inwardly projecting flanges 4 and 5 at its ends against the free edges of which 55 the face plate 3 fits, said flanges having lugs 6 on their edges extending through slots 7 in the face plate and bent over the outer side of said face plate to hold the latter firmly and securely in position. Between the two 60 plates 2 and 3 is disposed the tie member 8 of plate form, the reduced terminals 9 of which extend through slots in the two plates and which are headed against the outside 65 surfaces of said plates. The ends of the 70 body of the tie member or plate 8 fit solidly and substantially against the side plates 2 and 3. The tie member in addition to aiding in strengthening the casing-like frame 75 serves as a desirable means for the connection with the outer end of a spring as 10. Said spring is coiled around the main shaft or arbor 11, one end being suitably fastened to said main shaft and the other or outer end having a slot 12 to receive the lateral 80 projecting lug 13 of the tie member 8 which latter as will be obvious serves a double function. The main shaft or arbor 11 is supported by the side plates 2 and 3, the latter having openings or perforations to receive 85 said shaft, one end of the shaft being extended and threaded as at 14 to receive the key 15 by which said main shaft or arbor 11 can be turned to wind or tension the main 90 spring 10.

Rotative with the main arbor or shaft 11 is the ratchet wheel 16, the latter being internally corrugated and the shaft being externally corrugated as at 17, the projecting portions of the corrugated part 17 extending 95 between the grooves of the corrugations in the ratchet wheel, this presenting a convenient way of rotatively connecting the arbor 11 and ratchet wheel 16. The ratchet wheel has an elongated inwardly extending hub 18 which receives for rotation a driving or power transferring member such as the spur gear 19. Surrounding the inner end of the hub 18 is the friction disk 20, the marginal portion of which has a bearing against 100 the inner surface of the spur gear 19, the 105

disk 20 being located in the space between the spur gear and the main spring 10. This friction disk 20 rotates with the ratchet wheel 16, and this result may be secured by 5 staking or riveting the inner end of the hub over the central portion of the disk 20 as at 21. Pivoted upon the outer face of the spur gear 19 is the pawl 22 held constantly against the toothed portion of the ratchet 10 wheel 16 by the spring 23. Supported by the opposite side plates 2 and 3 and projecting outwardly therefrom is the shaft 24, the outer projecting ends of which may be provided with wheels as 25 rotative with 15 said shaft or axle 24. Located between the side members or plates 2 and 3 of the framing is the pinion 26 fastened to said shaft 24 and in mesh with the spur gear 27 which with the pinion 28 is carried by a shaft 29 20 supported by and between the plates 2 and 3. This pinion 28 meshes with a spur gear 30 which with the pinion 31 is fastened to the shaft 32 also supported by and between 25 said plates 2 and 3. The pinion 31 is in mesh with the spur gear or main driver 19.

If the key 15 be manipulated to turn the shaft or arbor 11 in the direction of the arrow applied for convenience to the spur gear 19 in Fig. 2, the spring 10 will be tensioned, 30 the key 15 being rotated until the requisite tension has been obtained and the pawl preventing accidental backward movement, while the spring is being tensioned. It is customary in toys to wind the spring 10 when the toy is off the floor. When the 35 spring is wound the wheels are placed on the floor and the key 15 freed. When this takes place with the toy shown, the spring 10 will unwind and will turn the shaft 11 in 40 a direction opposite to that in which said shaft is turned when the spring is being wound. The consequence will be that the rotating ratchet wheel acting against the pawl 22 will rotate the spur wheel 19 in a 45 direction opposite to the arrow applied thereto, so that with the wheels 25 on the ground the toy will be propelled in the direction of the arrow at the right thereof in Fig. 2. As the main arbor or shaft 11 is 50 turned under the action of the key 15, the spur gear 19 does not turn, it being as will be remembered, loosely supported by the hub 18. It will be assumed that the spring 55 has run down and that a child pulls the toy in the direction of the arrow in said Fig. 2. In this event the interposed train of gears in the casing-like frame all turn as does the spur gear 19, the latter rotating in a direction opposite to the arrow applied thereto.

and slipping over the friction disk 20 without applying its effect in any manner to the spring 10.

There may be associated with the axle 24 a governor device as 33, the shaft of which is geared to said axle. Said governor device 65 33 subserves its usual function.

What I claim is:

1. The combination of a main shaft, a 70 spring surrounding and connected with the main shaft, a ratchet wheel fastened to said main shaft, a power transferring member rotative with respect to the main shaft, a pawl cooperative with the ratchet and mounted upon said power transferring member, friction means between the power transferring member and the shaft, and a wheeled axle operatively connected with 75 said power transferring member.

2. The combination of a main shaft, a 80 coiled spring surrounding and connected with the main shaft, a ratchet wheel rotative with said main shaft and having an elongated hub, a power transferring member loose on said hub, a disk carried by said hub rotative therewith and having a friction 85 disk bearing against said power transferring member, a pawl pivoted on the power transferring member, and an axle operatively connected with said shaft.

3. The combination of a main shaft, a 90 spring surrounding and connected with said main shaft, a ratchet wheel rotative with said main shaft and having an elongated hub, a spur gear loose on said hub, a friction disk between the spur gear and the 95 spring, fitted on said hub, the hub being riveted over the disk to connect the disk with the hub for rotation therewith, a pawl on the spur gear for rotating said ratchet wheel, an axle, and operative connections 100 between said axle and said main shaft.

4. A frame comprising side plates and a tie member connecting said side plates between the ends thereof, a shaft supported by and between the side plates, a spring surrounding the shaft, one end of the spring being connected with the shaft and the other end having a slot, said tie member being provided with a lug extending through said slot, and an axle supported by said side 110 plates and operatively connected with said shaft.

In testimony whereof I affix my signature in presence of two witnesses.

HENRY W. WACHTELHAUSEN.
